UNITED STATES PATENT OFFICE.

OSWALD H. HANSEN, OF PORT WASHINGTON, WISCONSIN, ASSIGNOR TO HANSEN CANNING MACHINERY CORPORATION, OF PORT WASHINGTON, WISCONSIN, A CORPORATION OF WISCONSIN.

SEMI AUTOMATIC FILLER.

Application filed March 5, 1923. Serial No. 622,782.

This invention relates in general to improved apparatus for packing fruits, vegetables and other food products into containers, and relates more specifically to improvements in the construction and operation of semi-automatic can filling machinery and the like.

A general object of the invention is to provide various improvements in the construction of can filling machinery which will reduce such apparatus to its simplest form and which will enhance to a maximum the efficiency of operation thereof.

One of the more specific objects of the present invention is to provide a number of improvements in the construction of can filling machines of the type forming the subject of copending application Serial Number 518,243, filed November 28, 1921, which application specifically claims various novel features of construction disclosed but not claimed herein.

Other more specific objects of the present invention are as follows:—

25 To provide a relatively simple and compact semi-automatic can filling machine having maximum capacity and operable with minimum and relatively unskilled attendance.

30 To provide a filler which automatically and effectively delivers the bulk of the material to the successive cans, but which produces final product which is superior in quality to hand packed grades.

35 To provide can filling apparatus which is sanitary in every respect, in which material cannot collect or accumulate and become stagnant, and in which liquid drippings are effectively collected and disposed of.

40 To provide a can filler all parts of which are readily removable for inspection and cleaning, and various elements of which are conveniently adjustable to vary the conditions of operation.

45 To provide a neat and effective semi-automatic can filling mechanism in which a minimum amount of moving structure is exposed to the operators and in which danger of injury is reduced to a minimum.

50 To provide other improved details of con-

struction whereby the treatment of various kinds of material is facilitated and whereby the cost of manufacture is reduced to a minimum.

A clear conception of several embodiments of the present invention and of the mode of operation of machines constructed in accordance therewith, may be had by referring to the drawings accompanying and forming a part of this specification, in which like reference characters designate the same or similar parts in the various views.

Fig. 1 is a top view of an improved semi-automatic can filling machine having portions thereof broken away in order to more clearly illustrate sub-structure of the machine.

Fig. 2 is a sectional view of the improved semi-automatic filler, the portion to the left of the central axis being a radial section through the can supply mechanism, and the portion to the right of the central axis being a similar section through the material supply hopper.

Fig. 3 is a full top view of an improved semi-automatic can filling machine having a modified form of material supply means associated therewith.

Fig. 4 is a fragmentary central vertical section through the semi-automatic filler shown in Fig. 3.

Fig. 5 is a fragmentary enlarged central vertical section through the material supply means of the machine shown in Figs. 1 and 2, looking away from the central axis of the machine.

The improved semi-automatic can filling machine comprises in general a stationary central top plate 2; a rotary annular perforated distributing member 3 located below and adjacent to the peripheral edge of the plate 2; a stationary central rod 4 supporting the top plate 2; a rotary sleeve 5 journaled upon the rod 4 and in the stationary frame 6 and rotatably supporting the member 3; a can runway 7 supported by the frame 6 below the member 3; means for urging successive cans 19 along the can runway 7; mechanism for conducting the cans 19 to and from the machine; mechanism for impart-

ing motion to the various movable elements; and means for feeding material to the successive cans 19 through the perforations or openings in the member 3.

The stationary central top plate 2 is preferably constructed of sheet metal and is provided with a series of downwardly directed drain openings 17 for permitting free escape of liquid which may be deposited upon the plate. The top plate 2 is detachably connected to a supporting spider 24 which is rigidly attached to the stationary central rod 4. The central rod 4 is adjustably supported in the main frame 6 being locked against rotation relatively to the frame 6 by means of a set screw 26 coacting with a slot in the rod 4. An adjusting hand wheel 13 associated with screw threads on the rod 4 serves to vertically adjust the rod 4, spider 24 and top plate 2 relatively to the frame 6.

The annular rotary distributing member 3 surrounds the stationary top plate 2 and is provided with an annular series of downwardly directed openings 15 located closely adjacent to the periphery of the plate 2. The outer edge of the member 3 is preferably downwardly and inwardly inclined and the inner edge of the member 3 is preferably formed as an apron 16 adapted to direct liquid downwardly toward the central axis of the machine. An annular series of can hooks 8 are located one adjacent to each of the openings 15, the can hooks 8 and the member 3 being secured to a common spider 35 which is rigidly attached to the upper extremity of the driving sleeve 5. The sleeve 5 is rotatably supported upon a thrust bearing 25 secured to the stationary rod 4, and is rotatable about the rod 4 by means of a worm wheel 27 coacting with a worm 40 secured to one end of the counter-shaft 28. With the elements thus arranged, it will be noted that as the top plate 2 and spider 24 are vertically adjusted, the member 3 and can hooks 8 are simultaneously vertically adjusted.

The upper portion of the main frame 6 is provided with a curved can track or runway 7 disposed below the path of the openings 15 and of the hooks 8. The inlet and discharge ends of the runway 7 may be inclined in order to raise and lower the cans 19 relatively to the openings 15. A series of readily removable arc-shaped can guides 23 are located above the runway 7 and serve to maintain the cans 19 upon the runway 7 and in engagement with the can hooks 8. One or more of the can guides 23 may be provided with sectional guards 20 forming upright walls adjacent to the periphery of the member 3. By rigidly uniting the sectional can guides 23 and guards 20, the guides and guards may be readily simultaneously removed. Within the runway 7 is located a stationary drip catch or pan 12 adapted to

catch liquid delivered downwardly through the openings 17 and along the apron 16. The pan 12 may be provided with one or more drain openings 18 for discharging liquid to a suitable conductor. The drain openings 17, apron 16 and drip catch pan 12 insure rapid and effective delivery of excess liquid from the machine.

The machine is supplied with empty cans 19 by means of a can guide 14 which is capable of depositing the empty cans 19 in succession upon a continuously revolving tapered feed drum 10. The revolving tapered feed drum 10 is secured to the main driving shaft 30 which is rotatably supported in bearings in the main frame 6 and the inner end of which is provided with a bevel gear 29 which meshes with a bevel gear 39 secured to the counter-shaft 28. The delivery end of the feed drum 10 is provided with a helical projection 35 which is capable of gently delivering the successive cans in properly spaced relation against the successive advancing can hooks 8.

The filled cans 19 are delivered from the machine by means of automatic discharge mechanism 37 driven by worm gearing 38 associated with the counter-shaft 28. This discharge mechanism is of well known construction and requires no detail description herein. The main driving shaft 30 which communicates motion through the counter-shaft 28 to the various movable elements of the machine, is normally rotated automatically by means of motive power applied to the driving pulley 31 and from thence through a jaw clutch 32 to the shaft 30, but may be interchangeably operated manually by means of a hand wheel 11 secured to the outer extremity of the shaft 30. The clutch 32 may be manipulated either from the feed side of the machine by direct movement of the clutch operating lever 42, or it may be manipulated from the discharge side of the machine by indirect movement of the lever 42 through a lever 36 and a cross connection 34.

The material supply means disclosed in Figs. 1, 2 and 5, comprises a relatively large stationary hopper 9 located adjacent to the periphery of the stationary top plate 2 and having a lower discharge opening arranged directly above the movable openings 15 of the member 3. The hopper 9 is vertically adjustably supported upon a bracket 21, vertical adjustment of the hopper 9 being effected by means of an adjusting bolt 22. The lower portion of the hopper 9 is provided with a pair of curved walls or extensions 33 formed to guide the material delivered from the hopper in the general direction of advancement of the openings 15. A downwardly extending ridge or projection 44 located adjacent to the discharge opening of the hopper 9 serves as a holdback

for relatively large pieces of material. A horizontally pivoted flap 41 located between the extensions or walls 33 also serves to check the flow of material from the hopper 9 in the direction of advancement of the openings 15. The lower extremity of the flap 41 is preferably curved as indicated in order to produce uniform distribution of the material, and the flap 41 is preferably provided with an adjustable stop 43 for limiting the upward movement of the flap about its supporting pivot.

The material supply means illustrated in Figs. 3 and 4 comprises a relatively large chute 45 upon which certain materials may be deposited in bulk. The material thus deposited upon the chute 45 may be drawn with suitable scraping implements or by hand upon the stationary top plate 2, from whence the material may be delivered to the cans 19 through the successive openings 15.

During normal operation of the semi-automatic can filling machine disclosed in Figs. 1, 2 and 5, the various movable elements of the structure are simultaneously set in motion by applying power to the drive pulley 31 and by throwing in the jaw clutch 32. The empty cans 19 are delivered by gravity through the supply chute or guide 14 and are deposited by gravity upon the rotating can feed drum 10. The helical projection 35 of the feed drum 10 automatically delivers the successive empty cans 19 to the successive advancing can hooks 8. As the cans 19 engage the hooks 8, they are automatically positioned with their upper open ends directly below and in vertical alignment with the openings 15 of the revolving member 3. The successive cans 19 are then urged along the runway 7 and guides 23 until they reach the hopper 9 whereupon material from the hopper is automatically delivered by gravity through the openings 15 and into the subjacent cans 19 substantially filling the cans. Other material from the hopper 9 is urged past the flap 41 by means of the advancing member 3, the flap 41 and projection 44 automatically serving to prevent excessive delivery of material from the hopper 9. The material thus delivered from the hopper 9 past the flap 41 and projection 44 is conveyed between the extensions 33 where the cans 19 are further automatically filled with material. As the cans 19 and the member 3 are urged beyond the ends of the extensions 33, those cans which have not been properly automatically filled, are completely filled by one or more operators stationed about the periphery of the machine, these operators ordinarily removing excess material from one or more of the overfilled cans 19 and utilizing such material to properly supply the underfilled cans. Inasmuch as the cans 19 must travel considerable distance beyond the ends of the extensions 33 before

they are delivered from the machine, the operators have sufficient time to insure proper filling of all of the cans 19 even when the machine is being driven at maximum speed. The filled cans 19 are automatically discharged from the machine by means of the delivering mechanism 37 in a well known manner. It will be obvious that the successive cans 19 are automatically conducted to, through and from the machine, being practically automatically filled during their advancement.

By performing the major portion of the filling operation automatically, the manual handling of the material is reduced to a minimum and the final product is superior in quality to a hand packed grade. The operators are exposed to but a relatively small amount of moving structure and are protected against injury by the stationary top plate 2 and by the stationary guards 20 secured to the can guides 23. These guards 20 also serve to prevent splashing of the liquid over the attendants and upon the floor. Excess liquid from the material handled, is automatically and effectively discharged from the machine by the openings 17, the apron 16 and the drip catch pan 12, thereby preventing undesirable accumulation of liquid and drippings upon the machine frame and floor. Due to the fact that practically the entire filling operation is automatic, the machine may be operated at relatively high speed to produce maximum capacity. The projection 44 and flap 41 also serve to reduce the manual labor and to enhance the capacity of filling by automatically controlling the discharge of material from the supply hopper 9.

Practically all of the elements of the machine may be quickly and conveniently removed for inspection and cleaning. The hopper 9 and the elements associated therewith may be freely vertically removed at any time. This is also true of the modified supply chute 45. The stationary central top plate 2 may be removed by merely releasing the clamping nut from the upper end of the rod 4. The sectional can guides 23 and the guards 20 attached thereto may also be quickly removed to expose the cans 19 being filled. The can hooks 8 are preferably formed in sections for convenience of removal thus demonstrating the accessibility of the various elements.

The various elements are also readily adjustable to vary the conditions of operation. The can guide 14 may be adjusted to accommodate cans 19 of various sizes and the hand wheel 13 permits rapid vertical adjustment of the top plate 2, spider 24, rod 4, bearing 25, sleeve 5, can hooks 8 and member 3. The can hooks 8, member 3 and can guards 23 may be readily removed and other elements substituted in order to accommo-

date cans 19 of different sizes. The adjusting screw 22 permits ready vertical adjustment of the supply hopper 9, thus enabling adjustment of all of the more important elements with extreme rapidity.

The driving mechanism is also of extremely simple and compact construction and is controllable from various places around the machine. Manual operation of the machine may be effected by merely throwing out the jaw clutch 32 and manipulating the hand wheel 11 and the mechanism may be quickly started and stopped when desired.

It should be understood that it is not desired to limit the invention to the exact details of construction and operation herein shown and described, for various modifications within the scope of the claims may occur to persons skilled in the art.

20 It is claimed and desired to secure by Letters Patent:—

1. In a filling machine, a stationary top plate having downwardly directed drainage openings therein, a member movable about said plate and having an inner downwardly directed apron, and a drip catch pan below said openings and said apron.

2. In a filling machine, a movable member having a series of openings therein, a stationary hopper adapted to deliver material to said member in the direction of travel of said openings, and a pivoted flap adjacent to the delivery opening of said hopper, said flap being curved in the direction of movement of said member.

3. In a filling machine, a movable member having a series of openings therein, a stationary hopper adapted to deliver material to said member in the direction of travel of said openings, and a downwardly projecting wall associated with said hopper for retarding delivery of material from said hopper in the direction of movement of said openings.

4. In a filling machine, a rotary member having an annular series of openings therein, a stationary hopper adapted to deliver material to said member in the direction of travel of said openings, stationary guide walls for conducting material delivered from said hopper along the path of travel of said openings, and a curved flow retarding flap pivotally associated with said hopper between said walls.

5. In a filling machine, a rotary member having an annular series of openings therein, a stationary hopper adapted to deliver material to said member in the direction of travel of said openings, stationary guide walls for conducting material delivered from said hopper along the path of travel of said openings, a downwardly projecting wall spanning said guide walls for retarding delivery of material from said hopper, and a horizontally pivoted flow retarding flap located between said walls.

6. In a filling machine, a movable member having a series of openings therein, a stationary hopper adapted to deliver material toward said openings, means for effecting vertical adjustment of said hopper, and a pivoted flap adjacent to the delivery side of the opening of said hopper, said flap being curved downwardly and forwardly in the direction of movement of said member.

7. In a filling machine, a stationary top plate, a vertically adjustable rod supporting said plate, a perforated member movable about said plate, and a sleeve journaled on said rod for supporting said member.

8. In a filling machine, a stationary top plate, a central rod supporting said plate, a sleeve journaled on said rod, and an annular perforated member carried by said sleeve and movable about the periphery of said top plate.

9. In a filling machine, a main frame, a rod supported by said frame, a top plate secured to said rod, said rod and said plate being immovable relatively to said frame, an annular guide secured to said frame, a sleeve journaled on said rod, and an annular member secured to said sleeve and movable adjacent to said guide and to the periphery of said plate.

10. In a filling machine, a stationary circular top plate, a perforated member rotatable about the axis and beneath the peripheral edge of said plate, means for effecting simultaneous vertical adjustment of said plate and said member, and means for transporting cans with their upper open ends in direct communication with the perforations of said member.

11. In a filling machine, a stationary circular top plate, a perforated member rotatable about the axis and beneath the peripheral edge of said plate, means for effecting simultaneous vertical adjustment of said plate and said member, means for transporting cans with their upper open ends in direct communication with the perforations of said member, and a vertically adjustable material supply hopper having a discharge opening directly above the perforations of said member.

12. In a filling machine, a stationary circular top plate, a single annular member extending beneath the peripheral edge of said plate and having a series of downwardly directed openings located entirely beyond said edge, means for positioning cans beneath and in direct communication with the successive openings of said series, means for simultaneously moving said member and said can positioning means about the central axis of said plate, and a vertically adjustable material supply hopper located directly above said openings.

13. In a filling machine, a rotary annular perforated member, means for transporting

cans in a circular path beneath and with their upper ends in direct communication with the perforations of said member, a stationary circular top plate disposed within 5 the can circle and above the inner edge of said member, and a single central fastening for retaining said plate in position.

14. In a filling machine, a rotary annular perforated member having an elevated peripheral rim, means for transporting cans with and below the perforations of said member, a stationary circular top plate located above the plane of the upper ends of the perforations of said member but below 10 the top of said rim, and a stationary hopper having a discharge opening located between the periphery of said plate and the periphery of said rim, said hopper having a dis-

charge opening located below the top of said rim. 20

15. In a filling machine, means forming an annular series of can hooks rotatable about an axis, an annular member secured directly to and rotatable with said hooks, said member having openings formed to direct material into successive cans engaged by said hooks, and a circular top plate disposed above said hooks and said member and having a peripheral edge extending beyond the inner edge of said member, said hooks 25 and said member being simultaneously removable only upon removal of said plate.

In testimony whereof, the signature of the inventor is affixed hereto.

OSWALD H. HANSEN.
